METHOD OF MAKING HEAT EXCHANGERS

Bennett Lewis, Indianapolis, Ind.

Application January 26, 1939, Serial No. 252,862

7 Claims. (Cl. 113—118)

My invention relates to heat-transfer equipment and, in particular, to a method of forming a conduit for a fluid which either absorbs or emits heat in the operation of the equipment. An example of such a conduit is one form of evaporator used in refrigeration apparatus.

It has heretofore been proposed to make evaporators of this type with sheet-metal walls of double thickness, the two walls being formed to provide between them a space for the refrigerant. In some cases, this space has taken the form of a helical or retroverted channel successive passes of which are separated by bringing the two thicknesses of the evaporated wall into contact with each other. In cases where some leakage of the refrigerant directly from one pass of such a channel to an adjacent pass is of no particular moment, this construction has proved satisfactory; but, because of the difficulty of providing an effective seal between successive passes of the channel, it has heretofore been regarded as unsatisfactory for use in situations where it is necessary or desirable to ensure that all the refrigerant flows throughout the entire length of the channel.

It is the object of my invention to construct a device of the type described in which an effective seal is provided between successive passes of the refrigerant-channel so that by-passing of the refrigerant within the evaporator will be eliminated. A further object of my invention is to protect the device against corrosion.

In embodying my invention in a refrigerator evaporator, I form the evaporator with walls of double-thickness in such a way that between the walls there is provided a continuous refrigerant-passage having stretches which are contiguous and generally parallel, such stretches being separated by bringing the walls into contact between them. Then I cause to flow through the refrigerant-passage a sealing substance which will become deposited in the seams between adjacent stretches of the passage and will serve later to prevent refrigerant-flow from one passage to the other. Desirably, the evaporator is made of sheet steel, and the sealing substance is molten zinc, which, in addition to its sealing function, also resists corrosion. The zinc is caused to flow through the refrigerant-passage by immersing the complete evaporator in a bath of molten zinc, the passage being provided at suitable locations with openings for the entry of the molten zinc and for the egress of air. After the dipping operation has been completed and excess zinc

drained, these openings are then closed in any suitable manner.

The accompanying drawing illustrates my invention: Fig. 1 is an isometric view of an evaporator formed to provide within it an upwardly opening compartment for the reception of substances to be cooled; Fig. 2 is a fragmental vertical section through a wall of the evaporator shown in Fig. 1; Fig. 3 is a generally horizontal section through one corner of the evaporator shown in Fig. 1; Fig. 4 is an elevation illustrating the position occupied by the evaporator of Fig. 1 when it is to be dipped in the bath of sealing substance; Fig. 5 is an isometric view of a modified construction, partially completed; and Fig. 6 is a fragmental section on the line 6—6 of Fig. 5.

The evaporator illustrated in Fig. 1 is in the form of an open-top rectangular receptacle having side walls 10, desirably of sheet-metal. Extending around the side walls 10 of the receptacle is a strip 11 of sheet-metal formed with parallel grooves and having its ends brought together, as indicated at 12, in such a manner that the grooves form a continuous helical passage 13 about the receptacle. As shown in the drawing, two of the strips 11 are provided, one disposed near the bottom of the receptacle and the other near the top, the passages 13 formed by the strips 11 being interconnected in series by a conduit 14 and provided with inlet and outlet fittings 15 and 16 for connection into the refrigerating system.

Between successive turns of the passage 13, the material of the strip 11 is brought into contact with the side wall 10, as indicated at 16, and is secured thereto, desirably by welding.

The strip 11 is provided with openings 17 so disposed that when the strip is wrapped around the receptacle the openings will lie at diagonally opposite corners of the receptacle and will provide communication between the passage 13 and the atmosphere. After the strip or strips 11 have been secured in place, the receptacle is immersed in the sealing substance, the receptacle being so disposed during its immersion, as indicated in Fig. 4, that the diagonal between the two sets of openings 17 is approximately vertical. Thus the sealing substance may enter each turn of the passage 13 through the lowermost opening 17 therein, the air displaced by the entering sealing substance escaping through the other opening 17 at the top of the receptacle. If the device is formed of sheet-steel, molten zinc is a satisfactory sealing substance.

After the receptacle has been immersed for a

sufficient length of time, it is withdrawn and held in the position illustrated in Fig. 4 to permit un-deposited sealing substance to drain from its surface and from the surfaces of the channel 13. After the draining operation is completed, the openings 17 are closed.

Conveniently, the openings 17 are provided in the bottoms of recesses 18 formed by inward displacement of the material of the strip 11, each opening 17 being somewhat smaller in diameter than its associated recess. To seal each opening 17, a disc 19 of suitable material may be placed in the recess 18 and secured therein as by welding, soldering, or brazing.

An evaporator such as that described above possesses a continuous helical refrigerant-passage 13, the several turns of which are sealed from each other by the sealing substance deposited in the joint 16 as a result of the immersion above described. Cross-flow between adjacent turns of the helical passage is prevented, and all the refrigerant is compelled to flow through the passage from one end thereof to the other. Further, the metal of which the evaporator is formed is protected against corrosion by the zinc with which it is coated.

In the arrangement illustrated in Figs. 5 and 6, the device comprises two sheet-metal plates 21 and 22. The plate 22 is formed with spaced, parallel ribs 23 each of which extends inwardly from one end of the plate and terminates short of the opposite end to leave a short unribbed portion 24. The portions 24 are arranged alternately at opposite ends of the plate 22.

After the plate 22 has been formed in the manner described it is brought together with the plate 21 which closes the open tops of the channels between adjacent ribs 23. The two plates are then secured together, as by welding the ribs 23 to the face of the plate 21. Inlet and outlet fittings 26 and 27 are mounted in the ends of the outside channels.

The assembly thus formed is dipped in the sealing compound while held in position with the ribs 23 extending generally vertically, the sealing compound entering the channels at the lower ends thereof beneath the unribbed portions 24 of the plate 22 and displacing air which escapes from the upper ends of the channels. After immersion, excess sealing compound is drained off, and the edges of the unribbed portions 24 are brought into engagement with and secured to the plate 21, as by welding. (See dotted lines in Fig. 6 and the right-hand end of Fig. 5.) By this operation, the channels between the ribs 23 are connected in series to form a continuous retroverted passage.

I claim as my invention:

1. A process of making a heat-exchanger, comprising forming a plate of flexible material to provide a series of parallel ribs separated by open-topped channels, covering the open tops of said channels with a second plate engaging said ribs while leaving openings at the ends of said channels, securing said second plate to said ribs, immersing the assembly in a bath of liquid sealing material with some of said openings at the bottom of the assembly and others at the top and with the channels extending generally vertically between the upper and lower openings whereby the liquid sealing material may enter the lower openings and fill the channels while air escapes from the upper openings, removing the assembly from the bath to drain any excess sealing material from the channels through the lower open-

ings while air enters the upper openings, and subsequently closing said openings to leave said channels connected in series to form a continuous fluid passage.

5. 2. A process of making a heat-exchanger, comprising forming a plate of flexible material to provide a series of parallel ribs separated by open-topped channels, forming openings in the walls of said channels, wrapping said plate about a container having side walls which close said open-topped channels and, in such wrapping, disposing said openings at diametrically opposite points of said container, bringing the ends of said plate together so that one end of each channel is

10 aligned with the opposite end of an adjacent channel whereby the channels are connected together in series, securing the plate to the container and sealing the joint between its ends, immersing the container in a bath of liquid sealing compound in a position such that the diameter joining such openings is approximately vertical whereby the sealing material may enter the lowermost of said openings while air escapes through the uppermost openings, removing the 15 assembly from the bath of liquid sealing compound to drain any excess sealing compound through the lowermost of said openings while air enters the uppermost of said openings, and subsequently closing said openings.

30. 3. A process of making a heat exchanger, which comprises forming a plate of flexible material with a series of parallel spaced ribs separated by open-topped channels, each of said ribs ex-

35 tending inwardly from one end of the plate and terminating short of the other end to leave an unribbed portion, said unribbed portions being disposed alternately at opposite ends of the plate, covering the open tops of said channels with a second plate spaced from said unribbed portions

40 of the first plate to leave openings at the opposite ends of each channel, securing said second plate to said ribs, immersing the assembly in a bath of liquid sealing material with the ribs extending generally vertically whereby liquid sealing mate-

45 rial may enter the channels through the openings at the lower ends thereof while air escapes from the channels through the openings at the upper ends thereof, removing the assembly from the bath to drain excess sealing material from the channels through the openings at the lower ends thereof while air enters the openings at the upper ends thereof, bending the edges of said unribbed portions into association with said second plate, and sealing the joints between such edges and the second plate to interconnect said channels in series.

55. 4. The invention set forth in claim 1 with the addition that said plates are of sheet-metal and said sealing material is molten zinc, said ribs being secured to said second plate by welding.

5. The invention set forth in claim 2 with the addition that said plates are of sheet-metal and said sealing material is molten zinc, said ribs being secured to said second plate by welding.

6. The invention set forth in claim 3 with the addition that said plates are of sheet-metal and said sealing material is molten zinc, said ribs being secured to said second plate by welding.

7. A process of making a heat-exchanger, comprising forming a plate of flexible material to provide a series of parallel ribs separated by open-topped channels, forming openings in the walls of said channels, wrapping said plate about a container having side walls which close said

open-topped channels and, in such wrapping, disposing said openings at diametrically opposite points of said container, bringing the ends of said plate together at one side of the container with channel-ends at one end of the plate aligned with channel-ends at the opposite end of the plate, securing the plate to the container and sealing the joint between its ends, immersing the container in a bath of liquid sealing compound in a position such that the diameter joining such 10

openings is approximately vertical, whereby the sealing material may enter the lowermost of said openings while air escapes through the uppermost openings, removing the assembly from the bath of liquid sealing compound to drain any excess sealing compound through the lowermost of said openings while air enters the uppermost of said openings, and subsequently closing said openings.

BENNETT LEWIS.
